Karl W. Dall

Inventor
Benjamin Franklin
by Franklin Melville Hayes

UNITED STATES PATENT OFFICE.

BENJAMIN FRANKLIN, OF CHICAGO, ILLINOIS, ASSIGNOR TO SECURITY WINDOW GUARD COMPANY, OF CHICAGO, ILLINOIS, A CORPORATION OF ILLINOIS.

WINDOW-GUARD.

1,239,473.

Specification of Letters Patent. Patented Sept. 11, 1917.

Application filed January 24, 1916. Serial No. 73,788.

To all whom it may concern:

Be it known that I, BENJAMIN FRANKLIN, a citizen of the United States, and a resident of Chicago, in the county of Cook and State 5 of Illinois, have invented certain new and useful Improvements in Window-Guards; and I do hereby declare that the following is a full, clear, and exact description thereof, reference being had to the accompanying 10 drawings, and to the letters of reference marked thereon, which form a part of this specification.

This invention relates to improvements in window guards and consists of the matters 15 hereinafter described and more particularly pointed out in the appended claims.

The present invention is especially applicable to window guards of the kind illustrated and described in my prior Patent No. 20 1,110,678 bearing date of September 15th, 1914. The window guard forming the subject matter of said patent is not adjustable to windows of different widths, so that it is required to manufacture it in varied sizes, 25 to suit various standard widths of windows. The object of the present invention is to provide a window guard of the kind referred to with means for adjusting its width, so that but one size of window guard need be 30 made and kept on hand for use with windows of different widths.

A particular advantage in the use of the arrangement shown is that the guard or grating is in the form of a rigid structure, 35 the extensible fastening devices being so connected thereto as not to lessen the security of the guard or interfere in any manner with its normal operation. The form of connection between the sash, extensible bar and grating is such that so long as the bar is connected to the sash it cannot be disconnected from the grating. This function is inherent in the claimed structure and it is therefore unnecessary to rely upon secondary locks to insure the integrity of the 45 grating.

In the drawings:—

Figure 1 is a fragmentary view as looked at from the inside of a building, of a window 50 casing or frame illustrating my improved window guard attached in proper position and with the lower window sash in a partly open position.

Fig. 2 is a plan section view on an enlarged scale, the plane of the section being 55 indicated by the line 2—2 of Fig. 1.

Fig. 3 is a detail perspective view of the upper left hand corner of my improved guard as viewed in Fig. 1.

Fig. 4 is a detail vertical section on a 60 further enlarged scale, the plane of the section being indicated by the line 4—4 of Fig. 1.

Referring now in detail to that embodiment of my invention illustrated in the accompanying drawings:—10 indicates the window casing or frame and 11 the horizontal sill thereof. 12 and 13 indicate the upper and lower sash members adapted for vertical sliding movement in suitable guides 65 or runways forming a part of said casing.

14 indicates a vertically arranged channel member which is attached to the inner face of the upright side members 13^a of the lower window sash, there being of course one of 70 such channel members attached to each upright side member 13^a of said sash. The channel 14 is of a U-shape in cross section and is of a length approximating the vertical height of the member 13^a to which it is 75 attached by means of screws or in any other suitable manner. Extending approximately from top to bottom of said channel is a slot 14^a closed at its ends but having a circular enlargement 15 at its upper end. 80

16 indicates an anchor plate secured to the window sill, there being one of such plates (as in the construction illustrated in my prior patent), adjacent each upright member of the window casing. Said plate 90 is rectangular and has a centrally arranged tubular extension 16^a on its bottom side which is seated within a recess 17 formed in the sill 11. The plate is attached to the sill by means of screws 16^b with its top face 95 above the plane of the window sill. In said plate is provided an aperture 16^c which opens into the interior of the extension 16^a for a purpose which will presently appear.

20 indicates the window guard proper 100 which is of a height and width approximating the height and width of the average window sash. The exact height of the guard with reference to the height of the window is not as of great importance, but the width 105 thereof whereby it may be operatively en-

gaged with the upright channels 14 on the sash member 13^a is of importance as is readily apparent.

As in the case of the construction of my prior patent, the window guard is preferably made in the form of an open frame comprising upright side members or bars 21 and top and bottom horizontal members or bars 22 and 23. The frame is closed by a grating or like construction, capable of freely admitting light and air while at the same time preventing the passage through the frame of persons or children from the inside or of burglars or thieves from the outside. This frame is illustrated in the drawings as being closed by a grating made of laterally spaced bars 24, attached at their ends to the top and bottom horizontal members 22 and 23 of the frame 20 and braced at the middle by a bar 25.

The top and bottom members 22 and 23 of the frame and also the intermediate bar 25 are preferably made in the form of channel bars. The bottom member 23 and the intermediate member 25 are arranged with the channeled sides down, while the top member 22 is arranged with the channeled side up. A metal strip 27 is attached to the flanges of the top channel bar, thereby forming a tube substantially square in cross section.

30 indicates an L-shaped extension member comprising a relatively long arm 31 and a short arm 32 arranged at substantially right angles thereto. The long arm 31 is of such cross-section as to fit easily into the passageway in the top member 22 of the window guard. The short arm 32 is preferably made cylindric in cross-section and is reduced in diameter at its end, near which it is provided with oppositely facing notches 34. The end of the arm 32 is thus made capable of locking engagement within the slot 14^a of the channel 14, after its end has been thrust through the enlarged part 15 of said slot. The arm 31 of the member 30 may be adjusted lengthwise in the top horizontal member 22 of the window guard frame 20 so as to adjust it to window sashes of different widths. When the said member 30 is properly adjusted relative to the horizontal member 22 so that the short arm 32 thereof will register with the slot 14^a in the upright channel 14 on the window sash, 55 it is rigidly secured in its adjusted position by means of a set screw 33 extending through the inside flange of the top horizontal member 22 and engaged with the edge of the arm 31.

60 As in the case of the construction illustrated in my prior patent, the frame 20 is removably attached so that the lower sash may be freely raised and lowered as desired and when the sash is in a raised position, 65 the guard as a whole cannot be removed

from either inside or from outside of the window.

The bottom horizontal member 23 of the window guard is provided with depending, inwardly projecting hook members 27 which, as shown, are formed by extending the lower end of the outermost grating bar 24 below the horizontal channel 23, and bending the same inwardly to form the hook. The said hooks are adapted to be inserted through the apertures 16^b in the anchor plate 16 attached to the sill 11 so that when the guard as a whole is in an upright position, the said hooks will each lie within the tubular extension 16^a of the associated plate a short distance below the top of said plate. When in this position the bottom horizontal member 23 rests upon the rectangular top of the anchor plate, thus preventing the same from coming in contact with the sill to mar or injure it.

The guard is attached to the window sill having the anchor plates and a window sash having the upright channels 14 in the following manner. The lower window sash 90 must be in closed position. The frame 20 is then held in front of the sash with its top end inclined toward the interior of the room. The bottom horizontal member 23 is then moved to bring its inner edge into a position 95 of rest upon the inner margin of the anchor plate top and when in this position the hook members 27 are inserted through the apertures 16^b in said anchor plate tops. The frame 20 is then swung about the inner edge 100 of said bottom horizontal member as an axis into vertical position which brings the hooks into the interior of the anchor plate tubular extension 16^a in a manner permitting a slight amount of limited vertical play of 105 the guard as a whole. If the proper adjustment of the L-shaped bracket 30 has been previously made with respect to the horizontal top member 22 and slot 14^a in the channel 14, the free end of the short arm of 110 said member 30 will engage that part of the upright channel 14 defining the slots 14^a near the enlargement 15 at the upper end thereof. In this position it is apparent, the free end of the shorter arm 32 cannot be entered through the slot 14^a into the interior 115 of the channel 14. The guard as a whole may be then slightly raised until the hooks 27 engage with the bottom face of the top plate of the anchor plate, when the free end 120 of the short arm 32 of the member 30 is in register with the enlargement 15 at the upper end of the slot 14^a of the channel and through which it can now pass. A slight movement outwardly is given the upper end 125 of the guard so that the end of the short arm 32 passes through the apertures 15 after which the guard is allowed to drop until the bottom horizontal member 23 of the frame rests upon the top of the anchor 130

plates 16. The notches formed in the free end of the short arm 32 will then engage within the slots 14^a of the channel. To remove the window guard the operation for 5 attaching the same in place is just reversed.

If, when attaching the window guard it is found that the end of the arm 32 of the L-shaped extension member does not register or aline with the slots 14^a in the upright 10 channel 14, the set screw 33 in the upper horizontal member 22 is loosened and the extension member is moved inwardly or outwardly in the bar 22 until the proper adjustment is acquired. The set screw 33 is then 15 again tightened to secure the parts in the adjusted position.

While I have illustrated but one-half or one side of my proposed construction, it is apparent that the missing portion may be a 20 duplicate thereof.

I claim as my invention:—

1. In a window guard, the combination with the sill and sash of a grating in the form of a rigid structure, means at one end 25 thereof for engaging the sill, and extensible portions at each side of the grating, said portions being constructed to interlock with the grating and sash and being inseparable from the grating when both thereof are in 30 operative engagement with the sash, substantially as described.

2. In a window guard, the combination of

a grating in the form of a rigid structure, a frame member at one end of said structure being of tubular form and angular in cross 35 section, means at the opposite end of said structure for interlocking with a window frame, and a laterally extensible arm, one end of which is adapted to interfit with and telescopically engage said angular tube and 40 the other end of which is provided with means for interlocking with a sash, said arm being inseparable from said grating when in engagement with a sash, substantially as described. 45

3. In a window guard, the combination with the window frame and sash of a grating in the form of a rigid structure, means at one end thereof for engaging the window frame and a laterally extensible portion at 50 the opposite end of the grating said portion interlocking with the grating and said sash and being inseparable from the grating when in operative engagement with the sash, substantially as described. 55

In testimony, that I claim the foregoing as my invention I affix my signature in the presence of two witnesses, this 29th day of September A. D. 1915.

BENJAMIN FRANKLIN.
